RADIATOR CORE

Nicholas S. Diamant, Highland Park, Mich., assignor to Chrysler Corporation, Detroit, Mich., a corporation of Delaware

Application March 19, 1932, Serial No. 599,891

6 Claims. (Cl. 257—130)

This invention relates to an improved radiator core structure.

The main objects of the invention are to provide an improved radiator core of the type which has liquid courses that include joined corrugated plates having outwardly extending fins protruding from the vertices of the corrugations and constituting cell walls; to provide plate like spacing means between each adjacent pair of liquid courses of this character which are also corrugated and which form air cells in conjunction with the fins and corrugations of the liquid courses; to provide entirely closed protuberances on the sides of the ridges of the corrugated spacer plates which protrude into the cells so as to produce turbulence in the air flow therethrough; to provide protuberances of this character which have portions extending in advance of and on each side of the vertices of the ridges of the spacer plates; to provide imperforated spacer plates in a radiator core structure having liquid courses of this character which have substantial structural strength; to provide means on the sides of the ridges of corrugated spacer plates of this kind for aligning the vertices of the ridges thereof with the side edges of the fins which do not interrupt the contact between the vertices and fins or in any way impede the flow of solder along the entire lengths of these contacting portions. Further objects of the invention are to provide a pair of corrugated spacer plates between adjacent liquid courses of the type which have integral fins extending transversely of the space therebetween so as to form columns of liquid bound and air bound cells between the liquid courses; to provide entirely closed protuberances in the sides of the ridges of the spacer plates which extend far enough into the air and liquid bound cells to produce turbulence and which protrude beyond the vertices of the ridges so as to align the adjacent vertices of each pair of spacer plates with each other and the vertices of the ridges on the non-adjacent sides of each pair of spacer plates with the side edges of the fins of the liquid courses.

An illustrative embodiment of the invention is shown in the accompanying drawing, wherein:

Fig. 1 is an enlarged fragmentary elevation of one of the faces of a radiator core which embodies the invention.

Fig. 2 is a view similar to Fig. 1, showing another form of the invention.

Fig. 3 is an enlarged fragmentary elevation of one of the faces of a radiator core embodying

the invention and which has a pair of spacer plates between each pair of liquid courses.

Fig. 4 is an enlarged elevational view illustrating in detail the structure occurring at the junctions of the vertices of the fins and spacer plates shown in Figs. 2 and 3.

In the form shown in Fig. 1, my improved radiator core includes a series of spaced tortuous liquid courses 1 and 2, of which only two are shown. These liquid courses each comprises a 10 pair of corrugated plates 3 and 5 which have their longitudinal edge portions 6 and 7 soldered together. The intermediate portions of the plates 3 and 5 are offset outwardly with respect to each other so as to provide a passage for conducting 15 liquid cooling medium from the upper tank to the lower tank of a radiator. Integral fins 8 and 9 are formed on the plates 3 and 5, respectively, at the vertices of the ridges thereof. These fins extend transversely of the space between adjacent 20 liquid courses.

A corrugated spaced plate 10 is located between each pair of adjacent liquid courses 1 and 2 with the vertices of the ridges on opposite sides of the spacer plate contacting with the side edges 25 of the fins of the adjacent liquid courses. Each ridge of the corrugated spacer plate 10 includes a pair of converging panels or sides 11 on which are formed closed protuberances 12 that extend into the air cells 13 adjacent the liquid courses. 30 These hexagonal cells are called liquid bound cells and they are bounded on two sides by the plates of the liquid courses and on two opposite sides by the panels of the spacer plate, and the remaining sides are provided by the fins of the 35 liquid courses.

The protuberances 12, shown in Fig. 1, are preferably formed by pressing the metal of the panels of the spacer plate 10 outwardly from their respective planes with the aid of suitable 40 dies. These protuberances of adjacent sides of a ridge may register with each other or they may be formed in staggered relation to each other. In either event, however, each of the adjacent sides 15 of the opposite protuberances 45 of one ridge is substantially in the plane of that panel of the ridge which is opposite from the panel out of which the protuberance is formed, as indicated by the dot and dash line 30 in Fig. 1. This construction provides V-shaped notches 50 which serve as aligning means for retaining the vertices of the ridges and the side edges of the fins in alignment with each other. The completely closed protuberances produce turbulence 55 in the cells and they eliminate the necessity of

perforating the spacer plate or otherwise slitting the metal in order to align the vertices of its ridges with the fins of the liquid courses. Since each ridge of the respectively opposite sides of the spacer plate 10 contacts with a fin of the liquid courses, it is necessary to provide a protuberance 12 on both sides of each of the panels of the spacer plate 10.

In the form shown in Fig. 2, the liquid courses 1 and 2 are substantially identical in construction to the liquid courses described in the discussion of the form of my invention shown in Fig. 1, and the parts thereof are correspondingly designated by the same numerals. The spacer plate 14, which is located between the liquid courses, shown in Fig. 2, is also corrugated, but it is provided with protuberances 15 of a form which are entirely different from those shown in Fig. 1. The protuberances 15 are generally triangular in shape and they extend substantially from the vertex of one ridge of the spacer plate to the vertex of the next ridge on the other side of the spacer plate. These protuberances are arranged on the respectively opposite sides of the spacer plate 14 in staggered relation and each protuberance has an extremity 16 which extends beyond the vertex of the ridge on which it is formed so as to align the side edges of the fins of the liquid courses with the vertices of the ridges on respectively opposite sides of the spacer plate. The protuberances 15 extend a substantial distance into the liquid bound cells and are effective in producing substantial turbulence in the air flow therethrough. Since the protuberances are completely closed, they do not impair the structural strength of the spacer plate.

In the form shown in Fig. 3, a pair of corrugated spacer plates 17 similar to the type shown in my copending application, Serial No. 566,071, filed September 30th, 1931, are disposed between each pair of liquid courses 1 and 2. The vertices of the adjacent ridges of these spacer plates contact with each other and provide an intermediate row of air bound cells 18 and the vertices of the ridges on the non-adjacent sides of the spacer plates 17 contact with the side edges of the fins 8 and 9 of the liquid courses. The side faces or panels of the ridges of the spacer plates 17 are provided with alternate outwardly extending protuberances 19 and inwardly extending protuberances 20. The protuberances 19 project into the liquid bound cells 21 adjacent the liquid courses and the protuberances 20 project into the air bound cells 18, producing turbulence in the air flow through the respective cells. The protuberances 19 extend beyond the vertices of the corrugated spacer plates which contact with the fins 8 and 9 so as to properly align the latter with the vertices of the ridges. The extremities 22 of the protuberances 20 of one spacer plate which extend into the air bound cells 18 provide seats for receiving the ridges on the inner side of the other spacer plate. The extremities 22 of the protuberances 20 also extend beyond the vertices of the ridges adjacent which they are located so as to align the ridges on adjacent sides of the spacer plates with each other.

In order to assure proper alignment of the fins of the liquid courses with the vertices at the outer ridges of the spacer plate 17 in both the forms shown in Figs. 1 and 3, the latter are provided with arcuate shaped grooves 23 in which the rounded ends 24 of the fins are received. With this construction, substantial contacting surface

is provided between the spacer plates and fins for the purpose of rapidly conducting heat from the liquid courses to the spacer plates.

In each of the forms of the invention described above, the spacer plates are substantially imperforated and the vertices thereof contact continuously with the fins throughout substantially the entire length thereof. The continuous contacting engagement between the fins and spacer plates permits solder to readily flow along substantially the entire length of these parts, thereby producing metal to metal attachment between the fins and spacer plates, which greatly increases the dissipation of heat from the liquid courses to the spacer plates by conduction.

Although but several specific embodiments of the invention are herein shown and described, it will be understood that various changes in the size, shape, and arrangement of parts may be made without departing from the spirit of the invention, and it is not my intention to limit its scope other than by the terms of the appended claims.

What I claim is:

1. In a radiator core structure, a pair of plates 25 having edge portions sealed together and spaced intermediate portions providing a liquid course, spaced fins extending outwardly from said liquid course, and an imperforated corrugated spacer plate having the adjoining portions of the sides 30 of its ridges contacting continuously with the side edges of said fins throughout substantially their entire lengths and having closed turbulence producing protuberances projecting from the sides of said ridges beyond the adjoining 35 portions thereof and extending laterally of said sides of said ridges throughout the major portions of their widths.

2. In a radiator core structure, a pair of plates 40 having edge portions sealed together and having spaced intermediate portions providing a liquid course, spaced fins extending outwardly from said liquid course substantially normal to the length of said liquid course, a corrugated spacer plate having adjoining portions of the sides of 45 its ridges contacting with the side edges of said fins and providing in conjunction with said liquid course and fins a row of liquid bound cells, and closed turbulence producing protuberances extending throughout the main portion of the 50 width of the sides of said ridges from a location adjacent said adjoining side portions and projecting beyond the latter so as to align said fins and adjoining side portions, said protuberances being projected into said liquid bound cells for 55 producing turbulence in the air flow therethrough and having substantially closed front and rear sides of greater width than twice the thickness of said spacer plate.

3. In a radiator core structure, a pair of plates 60 having edge portions sealed together and spaced intermediate portions providing a liquid course, spaced fins extending outwardly from said liquid course, and a corrugated spacer plate including oppositely directed ridges comprising converging panels having their adjoining extremities 65 contacting continuously with substantially the entire lengths of the side edges of said fins for directing the flow of solder along the entire length of said ridges, the panels of each ridge 70 having turbulence producing protuberances thereon extending throughout the entire widths of said panels and the protuberances of each panel of a ridge having a side substantially aligned with the other panel of said ridge for 75

aligning the adjoining portions of said panels with said fins.

4. In a radiator core structure, a pair of spaced liquid courses, each including a pair of corrugated plates having spaced intermediate portions, fins on the adjacent sides of said liquid courses extending transversely of the space therebetween and substantially normal to the length of said liquid courses, said fins having the adjoining portions of the sides of the ridges of one side of said plate contacting with said edges of the fins of one liquid course and the adjoining portions of the sides of the ridges of the other side of said plate contacting with the side edges of the fins of the other liquid course, and a pair of closed turbulence producing protuberances on each of the sides of said ridges, having closed front and rear extremities extending transversely of the air flow through said core and across substantially the entire width of the sides of said ridges each protruding in the direction of one of said liquid courses and extending beyond the adjoining side portions of adjacent ridges of the opposite sides of said spacer plate, respectively, so as to align the side edges of said fins with said adjoining side portions and also for producing turbulence in the air flow between said liquid courses and said spacer plate.
5. In a radiator core structure, a pair of spaced liquid courses, each including a pair of corrugated plates having edge portions sealed together and spaced intermediate portions, fins extending outwardly from the vertices of the ridges of adjacent plates of said liquid courses, a corrugated spacer plate between said liquid courses having the adjoining portions of the sides of the ridges on one side thereof contacting with the side edges of the fins of one liquid course and the adjoining portions of the sides of the ridges of the other side thereof contacting

with the fins of the other liquid course providing a row of substantially hexagonal liquid bound cells adjacent each of said liquid courses, and closed turbulence producing protuberances extending outwardly in opposite directions from the opposite sides of the ridges of said spacer plate into said liquid bound cells for producing turbulence therein and having portions extending beyond the adjoining portions of the sides of said ridges for aligning said fins with said adjoining side portions, said protuberances having substantially closed front and rear sides extending laterally of and throughout the main portions of the widths of the sides of said ridges.

6. In a radiator core structure, a pair of spaced liquid courses, each including a pair of corrugated plates having spaced intermediate portions, fins on the adjacent sides of said liquid courses extending transversely of the space therebetween, spacing means between said liquid courses including a pair of corrugated spacer plates having ridges on their opposite sides provided with adjoining panel portions, the adjoining panel portions of the ridges of adjacent sides contacting with each other and the adjoining panel portions of the ridges of non-adjacent sides contacting with the side edges of the fins of said liquid courses respectively, and closed turbulence producing protuberances extending across the major portion of the width of said panel portions and projecting outwardly from the respectively opposite sides of said spacer plates and protruding beyond the adjoining panel portions of the ridges thereof for aligning the adjacent ridges of said spacer plates with each other and the ridges of the non-adjacent sides of said spacer plates with said fins as well as producing turbulence in the air flow adjacent said spacer plates.
